G. W. ODELL

TIME CARD

Filed June 29, 1921

Inventor
George W. Odell,
By his Attorneys
Kerr, Page, Cooper & Hayward

UNITED STATES PATENT OFFICE.

GEORGE WILLIAM ODELL, OF BINGHAMTON, NEW YORK, ASSIGNOR TO THE INTERNATIONAL TIME RECORDING COMPANY OF NEW YORK, A CORPORATION OF NEW YORK.

TIME CARD.

Application filed June 29, 1921. Serial No. 481,197.

To all whom it may concern:

Be it known that I, GEORGE W. ODELL, a subject of the King of Great Britain, residing at Binghamton, in the county of Broome and State of New York, have invented certain new and useful Improvements in Time Cards, of which the following is a full, clear, and exact description.

In certain branches of industry it is usual 10 at the present time to have each employee make and preserve a record of the time spent on each job, for which purpose it is customary to use some form of time recorder into which the workman inserts a card at 15 the start and finish of a job, and thereby prints or otherwise records thereon what is commonly known as his "on" and his "off" times. Some of these records print, others punch and still others cut out certain 20 sections of these cards, from which cut-out sections, by another machine, the elapsed time is computed, printed or recorded and, if the card is punched with a definitely placed slot or perforation to indicate the 25 rate of pay, the total amount due the workman for the time put into that particular job is also recorded.

I have heretofore devised and patented 30 both cards and recorders of this last-named type, and for a more ready understanding of the art as it existed prior to the invention upon which is based the present application for Letters Patent, by those not familiar with such art I may refer to my 35 Patents No. 1,221,895, dated April 10, 1917, and No. 1,250,494, dated December 18, 1917.

In these patents a card was inserted into 40 the recorder and the latter operated to cut out along one side a section of a length from the corner dependent upon and indicating the "on" time. At the finish of the job the same card was again inserted in the machine and automatically a section was 45 cut out from the opposite edge of the card of a length from the corner corresponding to the time at which the second insertion was made. Thus, cards were produced having at one end sections cut out from the corners at one end along opposite edges, of different 50 lengths, and a properly designed machine, into which such cards were introduced, computed and set up a record of the

elapsed time and money value corresponding to the difference in the lengths of the two cut out sections.

The present invention involves a recorder of this general type, but differing from that referred to in that when a card is introduced for the "on" time, it cuts out a section along one edge at each end of the card, 55 one to indicate the minutes, the other the hours and records the fact that this card received such record. On the second or "off" introduction of the card, the recorder cuts out a section at each end along the opposite edge of the card, one section indicating the minutes, the other the hours of the 60 time of the second introduction and records this fact so that further insertion will not alter the record already made. Each card, 65 therefore, that indicates the elapsed time of a finished job (assuming it to have been inserted in the machine at other times than exactly on the even hour), will contain four 70 cutout sections, two on each edge and at opposite ends of the card, the first $\frac{1}{16}$ of the cuts on the minute side being always made to indicate to the machine the number of times the card has been inserted.

There is a marked and important advantage in thus cutting a card, as in the first method above described the length of the cards required was almost prohibitive in practical operations, while by the method which is here involved a much smaller and shorter card is required for any ordinary record.

A card thus cut may be placed in another machine which automatically computes and records the elapsed time and money value indicated by the cuts on the two edges, and makes, if necessary, other computations. Such machines are well known in this art, and I shall not go into a description of their character or mode of operation, as neither is in anyway involved in the special improvement of this application which resides in the improved card above described. The recorder for cutting such cards is made 95 the subject of another application.

In the accompanying drawings I have shown the improved card in its three forms or conditions. Fig. 1 shows the card before being used; Fig. 2 the same card after its

first insertion into the recorder, and Fig. 3 the same card after its second insertion, or in the condition in which it indicates the "on" and the "off" times of a job.

5 The card is composed of the material commonly employed for workmen's time cards, and is made of the usual size, substantially that shown. In one edge, or that which is designed to pass into the recorder on the 10 first insertion, is a notch or cut-away portion 1. At one end, for convenience, a scale of nine equal parts 2 is printed on both edges, and at the opposite end a scale 3 of as many equal divisions as there are hours 15 in the working day is also printed.

In the present case the minute scales 2, have nine divisions as the cutters of the recording machine which cut out the cards under the scales move one step or the length 20 of one division once every six minutes or nine times each hour, and these minute scales which mark the sections to be cut out do not begin at the corners but at certain distances therefrom. In other words, 25 there are blank spaces 4 at the minute end of the card.

Let it be assumed that a working day begins at 6 a. m. and ends at 5 p. m. with one hour for dinner, and that a workman 30 begins a certain job at 7:30 a. m. He inserts his card into the recorder which has cutters that are moved by time-controlled mechanism and which, on the first insertion, cut out a section on the minute side 35 equal in length to the aggregate of five sections plus the blank space, and on the hour side one section. The recorder also prints on the margin of the card the word "Start" in one or more places.

40 When the job is finished, say, at six minutes past three, the card is again inserted into the recorder, which is properly designed so as not to again cut the starting edge, but which cuts out on the minute end 45 a section equal to one division of the scale plus the blank space, and on the hour end a section equal to the aggregate length of eight hour divisions, and the card, when removed from the machine, will appear as 50 in Fig. 3, with the word "Finish" printed at one or more points in the margin.

Of course, in practice, an automatic recording or cutting machine is used, and as the operation of such machine is determined 55 solely by the configuration of the cards, it is essential that a section corresponding to the blank spaces be cut out from one corner of the minute end of the card, wherever the minute cutters happen to be at the moment of the first insertion, so that upon the second insertion the mutilated card will operate the cutters on the opposite side of the card. It is also essential that the part

1 be cut out to determine the edge of the card which must be inserted first.

The fact, however, that the cards, in practice, will be cut by a machine is not a relevant fact to this invention for they might be cut or punched by a clerk by hand and printed by hand at the beginning and end of a job. So, also it is immaterial that the finished card is passed into a machine which measures the length of the cut-out sections, compares their length and computes the elapsed time accordingly, for this might also be done by a clerk with a rule, a pair of calipers, and the elapsed time figured out from the difference in the lengths of the cut-out sections on opposite sides of the card.

In the card herein shown is a perforation 42. The position or character of this perforation indicates the rate at which the workman is to be paid. This is not new, however, and requires no further description herein. It may also be observed that the minute divisions on the card are shown at the left- and the hour divisions at the right-hand ends of the card. This is, of course, immaterial as these positions may be used in practice, or reversed.

What I claim is:—

1. A workman's card for showing the time spent on a given job, having scales along each edge at one end corresponding to given fractions of an hour, and at corresponding points at the opposite edge scales with divisions corresponding to the hours of a working day, whereby the starting time in hours and minutes may be indicated by sections cut out from one edge, and the finishing time by sections cut out from the other edge.

2. A workman's card indicating the elapsed time on a given job, having cut-out sections along each edge at one end of lengths corresponding to the fractions of one hour and along each edge at the opposite end of lengths corresponding to the hours of a working day at which the starting and finishing times were recorded.

3. A workman's card indicating the elapsed time on a given job, having a cut-out section on the "on" edge or that on which the starting time is recorded, and cut-out sections along each edge at one end of lengths corresponding to the fractions of one hour plus a given blank space, and along each edge at the opposite end of lengths corresponding to the hours of a working day at which the starting and finishing times were recorded.

In testimony whereof I hereto affix my signature.

GEORGE WILLIAM ODELL.
